UNITED STATES PATENT OFFICE.

DE WITT BRUCE AND WILLARD M. DELAVAN, OF PITTSFIELD, MASSACHUSETTS, ASSIGNEES TO TRIUMPH VOTING MACHINE COMPANY, OF PITTSFIELD, MASSACHUSETTS, A CORPORATION OF NEW JERSEY.

VOTING-BOOTH.

No. 831,703.

Specification of Letters Patent.

Patented Sept. 25, 1906.

Application filed February 15, 1906. Serial No. 301,321.

To all whom it may concern:

Be it known that we, DE WITT BRUCE and WILLARD M. DELAVAN, citizens of the United States, residing at Pittsfield, county of Berkshire, State of Massachusetts, have invented a new and useful Voting-Booth, of which the following is a specification.

This invention has for its object to provide a portable knockdown voting-booth adapted for general use at elections, and especially adapted for use in connection with voting-machines.

With this and other objects in view we have devised the novel sectional voting-booth of which the following description, in connection with the accompanying drawings, is a specification, reference characters being used to indicate the several parts.

Figure 1 is a plan view of our novel voting-booth with the roof removed; Fig. 2, a side elevation on a reduced scale, the point of view being from the bottom of the sheet in Fig. 1; Fig. 3, an end elevation, the point of view being from the right in Fig. 1; Fig. 4, a detail view, on an enlarged scale, showing one of the sides and a portion of the roof in end elevation; and Fig. 5 is a detail view, on an enlarged scale, illustrating a mode of joining the sections.

The idea of our present invention is to render it unnecessary to hire rooms for voting purposes or to build frame structures, but to avoid this expense and inconvenience by providing sectional structures which will be durable, weatherproof, light, and easy to transport, will occupy but relatively little space in storage, and can be easily and quickly put up on any vacant space by persons of ordinary skill. The special size and shape of the building is of course not of the essence of the invention. In the drawings we have illustrated a building consisting of fourteen vertical sections, four on each side and three at each end. The floor may or may not be laid in sections. The roof is preferably made in sections corresponding in number with the side sections.

10 denotes side sections; 11, end sections; 12, roof-sections; 13, flooring, and 14 top cross-pieces.

In the present instance we have illustrated a voting-booth arranged for two voting-ma-

chines, which are indicated by 15. The booth is provided with one entrance (indicated by 16) which is placed at one end near the corner, the right upper corner, as shown in Fig. 1, and with one exit, which is placed near the middle of one of the sides, the side at the bottom of the sheet, as indicated in Fig. 1. The entrance and exit are preferably provided with doors, as indicated by 18. Voters entering the booth pass along an entrance-passage (indicated by 19) to a turnstile, (indicated by 20.) At the turnstile the voters are checked in the usual manner on voting-lists by checkers within the checker's space, (indicated by 21.) After passing the checkers or other officials the voters are directed in either direction, as indicated by the arrows. In the passage, (indicated by 22,) the voter faces the back of a voting-machine. He then operates the entrance-lever 23 of the voting-machine, and passes around to the front of the machine where he votes, standing in the voting-space, (indicated by 24.) After voting the voter operates the exit-lever 25 of the voting-machine and passes through exit-passage 26 to the exit. Half of the voters are supposed to pass in one direction and vote at one voting-machine and half in the opposite direction to vote at the other voting-machine. Voters passing in the opposite direction from that already described pass along passage 27 and face the back of the other voting-machine, it being understood, of course, that no voter is allowed to enter either passage 22 or 27 until the last voter has completed the operation of voting and has operated the exit-lever of the machine in that passage. The voter in passage 27 operates the entrance-lever 23 of the voting-machine in that passage and passes around to the front of the machine, where he votes, standing in the voting-space, (indicated by 28.) After voting the voter operates the exit-lever 25 of the voting-machine and passes through exit-passage 29 to the exit. Exit-turnstiles 30 are shown in exit-passages 26 and 29, although, if preferred, a single turnstile may be placed at the exit, as indicated by dotted lines. The entrance and exit turnstiles, or either of them, may or may not be provided with registers to indicate the number of voters passing. A voter standing in voting-space 24 and voting at the left vot-

ing-machine, as seen in Fig. 1, is wholly concealed from the view of the officials in the checker's space.

In order that a voter standing in voting-space 28 and voting at the right voting-machine, as seen in Fig. 1, may be wholly concealed from the view of the officials in the checker's space, we provide a partition 31, which wholly conceals him from view. The other passages and spaces are merely separated by railings, (indicated by 32,) supported by posts, (indicated by 33.) Another partition 34 at the right of the right voting-machine renders it impossible for a voter to pass from entrance-passage 19 to exit-passage 29.

The sections of which the booth is composed may be made of any suitable material, as canvas or sheet metal, secured to suitable framework or a wooden sheathing secured to suitable framework. The roof-sections likewise may be made of canvas, sheet metal, or wooden sheathing. Skylights, (indicated by 35,) are provided in the roof over the checkers' and voting spaces and elsewhere, if desirable, and windows 36 may be placed in the sections as required. The side and end sections are provided at their mid-length and at their upper ends with transverse strips 37, which are mortised into vertical strips 38, the parts being secured together in any suitable manner, as by bolts or locking-strips, (not shown,) as they are not of the essence of the invention.

Having thus described our invention, we claim—

- 35 1. A voting-booth comprising an entrance-passage, passages leading in opposite directions therefrom, voting-spaces to which said passages lead, a checker's space intermediate the voting-spaces, and exit-passages leading from the voting-spaces.
- 40 2. A voting-booth comprising an entrance-passage, passages leading in opposite directions therefrom, voting-spaces to which said passages lead, a checker's space intermediate the voting-spaces, and exit-passages leading

from the voting-spaces and terminating at a common exit.

3. A voting-booth comprising an entrance-passage, a turnstile in said passage, passages leading therefrom in opposite directions, voting-spaces to which said passages lead, a checker's space intermediate the voting-spaces, exit-passages leading from the voting spaces to a common exit, and a turnstile intermediate the voting-spaces and the exit. 55

4. A voting-booth comprising an entrance-passage, passages leading in opposite directions therefrom, voting-spaces to which said passages lead, a checker's space intermediate the voting-spaces, a partition partly inclosing one of the voting-spaces, for the purpose set forth, and exit-passages leading from the voting-spaces. 60

5. A voting-booth comprising an entrance-passage, passages leading in opposite directions therefrom, voting-spaces to which said passages lead, a checker's space intermediate the voting-spaces, exit-passages leading from the voting-spaces and railing, by which said passages and spaces are defined. 70

6. A knockdown voting-booth comprising end and side sections, one end section being provided with an entrance and one side section, with an exit, transverse strips on the side and end sections, intermediate vertical strips engaged by the transverse strips, top cross-strips, roof-sections secured to the side and end sections, and railings by which the interior is divided into an entrance-passage, passages leading in opposite directions therefrom, voting-spaces, a checker's space intermediate the voting-spaces and exit-passages leading from the voting-spaces. 75 80

In testimony whereof we affix our signatures in presence of two witnesses.
